UNITED STATES PATENT OFFICE.

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE.

PILE WIRE.

Application filed November 1, 1920. Serial No. 420,963.

To all whom it may concern:

Be it known that I, RALPH E. THOMPSON, a citizen of the United States, residing at Brookline, in the county of Norfolk and State of Massachusetts, have invented certain new and useful Improvements in Pile Wires, of which the following is a specification.

My invention relates to pile wires such as are used in looms for weaving cut-pile fabrics and are provided with cutting blades which are detachable, so that when a blade becomes dull from use it can be replaced by a sharp blade. The object of the invention is to provide for the secure attachment of the blades to the wires without the use of any additional parts for holding the blades in place, and to this end I employ a blade which, while normally flat, is thin enough to be flexible transversely and I construct it and the tip portion of the wire in such manner that it is necessary to flex the blade in order to locate it in operative position in the recess provided for its reception. When this position is reached the blade resumes its original flat condition, and so long as it remains flat it cannot be displaced within the recess, or removed therefrom. Consequently it is necessary to flex the blade in order to disconnect it from the wire, this being prevented during use by the inherent elasticity of the blade.

My invention may be embodied in various forms, one of which is illustrated by way of example in the accompanying drawings, in which,

Figure 1 is a side elevation of a portion of a pile wire made in accordance with my invention:

Figure 2 is a transverse section on the line 2—2 in Figure 1; and

Figure 3 is a side view of the detachable blade shown in Figures 1 and 2.

Referring to the drawings, 2 indicates the free or front end portion of a pile wire which, except as hereinafter described, may be of any usual or desirable construction, its tip 3 being enlarged vertically and bent laterally at its extremity as is customary. At the rear portion of the tip there is provided a recess for the reception of a detachable blade 4, which is normally flat and is of such thinness that it can be readily flexed transversely. The lower edge of the

recess, which is just wide enough to receive the blade and has its end walls 5 and 6 shaped to overhang the ends of the blade when seated in the recess, the end wall 5 being located in transverse alignment with the front wall of an aperture 7 which extends through the tip from side to side. The parts above described are so proportioned that when ready for use the front end of the blade lies directly behind the end wall 5 and its cutting edge 8 slants downward and rearward slightly above the slanting rear edge of the tip, in position to sever the loops of yarn surrounding the wire 2 when the latter is withdrawn.

To insert the blade its rear end is introduced into the recess near the rear end of the latter, its front end being bent to one side of the tip in front of the aperture 7, and is then pushed downward and rearward until its front end is in position to spring into place behind the end wall 5, whereupon the blade resumes its normal flat condition. So long as it remains flat it is prevented from being removed from or displaced within the recess by the side and end walls of the latter, of which the end walls 5 and 6 prevent the blade from moving upward or lengthwise, so that in order to remove the blade it is necessary to bend its front end laterally beyond one side of the end wall 5 and then draw it forwardly and upwardly out of the recess, and since the blade while in use is not subjected to any strains tending to flex it laterally there is no danger of its accidental disconnection from the wire.

The construction above described has the advantages that the tip is of uniform thickness throughout and its sides are smooth and free from projections of any sort, the aperture 7 being located above the tops of the loops formed over the wire, so that the loops are necessarily severed before the yarn can reach any opening in which the flights can catch. It will be evident, however, that my invention may be embodied in wires having variously shaped blades and recesses adapted to utilize the flexibility and elasticity of the blades for securing them in operative position.

I claim:

1. A pile wire having a recess adapted to receive a normally-flat flexible blade and an open space at one end of the recess into

which one end of the blade may be flexed laterally, the end walls of the recess being shaped to overhang the ends of the flat blade while seated on the bottom of the

5 recess.

2. A pile wire having a recess adapted to receive a normally-flat flexible blade and a transverse aperture communicating with one end of the recess in position to receive the adjacent end of the blade when flexed laterally, the end walls of the recess being shaped to overhang the ends of the flat blade while seated on the bottom of the recess.
- 10 3. A pile wire provided with a recess and with an adjacent space communicating therewith, in combination with a normally-

flat flexible blade shaped to lie flat within the recess and to be flexed into the adjacent space while seated on the bottom of the recess, and means for preventing movement of the blade in its own plane while flat.

20 4. A pile wire provided with a recess and with an adjacent space communicating with one end of the recess, in combination with a normally-flat flexible blade adapted to seat on the bottom of the recess and to be flexed at one end into the adjacent space, the ends of the recess being shaped to engage the ends of the blade and prevent upward movement thereof while flat.

25 Signed at Boston, Mass., this 29th day of Oct., 1920.

RALPH E. THOMPSON.
